UNITED STATES PATENT OFFICE.

WILLIAM SCOTT, OF MALDEN, MASSACHUSETTS.

VALVE FOR WATER-CLOSETS.

SPECIFICATION forming part of Letters Patent No. 331,556, dated December 1, 1885.

Application filed January 7, 1884. Serial No. 116,601. (No model.)

To all whom it may concern:

Be it known that I, WILLIAM SCOTT, of Malden, in the county of Middlesex and State of Massachusetts, have invented certain new and 5 useful Improvements in Valves for Water-Closets, &c., of which the following is a full, clear, and exact description.

This invention relates to float-valves having passages for the ingress and egress of air 10 and water, and arranged in connection with the discharge-pipe of a water-tank or other tanks containing liquids, to be opened for the discharge of the liquid in the tanks through said discharge-pipe, and to be closed from the 15 action of the liquid in the tank upon the valves; and it consists in a construction of the valve for said water and air passages, and in the arrangement of mechanism for operating valves of water-closets, &c., all substantially as hereinafter described.

In the accompanying plate of drawings, Figure 1 is a vertical section of the valve, water-tank, and discharge and overflow pipes thereof, with the operating mechanism for the 25 valve in side elevation. The valve is closed, and its operating mechanism in its normal position of rest. Fig. 2 is a side elevation of the valve discharge and overflow pipes thereof, and operating mechanism for the valve, showing the valve in one of its open positions, as 30 also its operating mechanism in the corresponding position therefor. The tank is in vertical section. Fig. 3 is a similar view to Fig. 2, but showing the valve as in another of 35 its open positions, as also its operating mechanism in the corresponding position therefor.

In the drawings, A is a water-tank, and B an outlet or discharge pipe leading from it, and C the overflow-pipe in communication 40 with discharge-pipe, all and otherwise, except as hereinafter particularly described, as usual in the water-system of dwelling-houses, hotels, and other buildings.

D is a hollow or chambered valve, made of 45 sheet metal or of other suitable material and of suitable shape—as, for instance, hemispherical—and its upper side, E, is convex, and its under side, F, is flat, and it is provided with a washer or packing-disk, a , of 50 leather or other suitable material, which, when the valve is closed rests upon and makes close

contact with the upper end or seat, G, of the outlet-pipe B, opening into and leading from the tank, and thus closes said pipe to the escape through it of water from the tank. The 55 valve-seat G is below the water-level of the tank, and the valve D, at rest thereon and closed, is wholly submerged in the water of the tank.

b is a vertical passage, made of a tube, H, 60 which is inserted in the lower side, F, of the valve, and opens to the valve-chamber J at its lower portion, and this tube H, when the valve is closed, enters into the open end of a vertical pipe, K, leading from the tank at the 65 upper open end of its discharge-pipe.

d is another vertical passage, made of a tube, L, which leads from and opens to the upper portion of the chamber J of the valve, and passes through and out of the bottom of 70 the valve downward in a line coincident with the vertical axis of the discharge-pipe and through a fixed horizontal guiding-collar, M, of said discharge-pipe, and at its lower end below said collar, has a shouldering collar, N. 75 The fixed guide-collar M is left open about it for the free passage of water from the tank through the discharge-pipe when the valve is opened, and the shouldering collar N of the vertical tube L acts as a stop by abutting 80 against the under side of said fixed collar M, to the upward movement or lift of the valve from its seat G, when the valve is opened, as will hereinafter appear.

The two passages b and d, above described, 85 make communication with the chamber J of the valve, and are respectively for the ingress and egress of the water of the tank and of air.

By arranging the air pipe or passage d in 90 the peculiar manner set forth and shown the stem of the valve D is made to subserve two purposes—namely, to act as a guide for the valve and as an air-pipe.

It is more desirable and simple to have the 95 air-pipe arranged as stated rather than to extend it upwardly through the water above the water-level, for the reason that such upward extension requires a great length of pipe, it makes a more rigid connection between the 100 valve and its operating mechanism, and its tendency is to incline or cant to one side,

thereby producing friction between the valve guide-stem and the bearings thereof, which detrimentally affects the working and seating of the valve.

5 The valve with its downwardly-extending air-pipe more quickly empties of its contents, for the reason that the rush of water through the pipe exhausts the air in the valve and no air can enter to replace it, as it can in a valve 10 having the air-pipe extending upward.

O is a vertical stem extending upward from the upper convex side, E, of the valve, and in a line coincident with the vertical axis of the upward and downward movement of the valve 15 as it is guided by the tubular air-passage d L, which passes through the fixed guide-collar M. This stem O at its upper portion passes loosely through the cross-piece g, which makes the lower end of a vertical and rectangular 20 shaped link or yoke, P, and above said cross-piece, within said yoke, said stem O has a shouldering collar, h. The yoke at its upper end is suspended from the horizontal arm Q of a lever, R, which turns upon a fixed horizontal 25 fulcrum-pin, k, of a stationary standard, S, and at its upper edge, over its fulcrum k, has an upward-projecting nose, T, rounded at its upper end, l, and upon one side, m, its other side, n, being substantially straight and vertical. 30 The lever R in its normal position rests by its arm Q, connected, as above described, to the valve D, upon a stationary stop or rest block, T², suitably located therefor.

U is another horizontal lever located above 35 the lever R, and, as shown, in line therewith. This lever U has a slot or elongated opening or bearing, q, Figs. 1, 2, and 3, by which it is hung on a fixed horizontal pin, r, of the standard S, and the lever is made with an upward-projecting crank-portion, X. The arm V of 40 the upper lever, U, is provided with a weight, Y, suitably adapted to be adjusted thereon to increase or decrease the leverage to be exerted by said lever on the valve, as will hereinafter appear, and its arm W projects downward toward and in line with the arm Z of the under lever, R, and carries at its outer end an adjustable vertical set-screw, t, making at its end d², when the two levers are at rest 45 and in their normal positions, Fig. 1, and for a certain portion of the swing of the levers U R upon their respective fulcrum-pins, a bearing upon the upper surface, f², of the horizontal projection A² at one side of the arm Z of 50 the lower or "valve lever" R, as it will be hereinafter designated for convenience.

The upper or "operating" lever, as it will be hereinafter designated for convenience, in its normal position rests against an abutment, B², 55 of the standard S. The operating-lever U, between its arms V W, on its under edge, has a downward-projecting nose, C², having a straight vertical side or edge, a², and a rounded vertical side or edge, b². The nose of the 60 operating-lever U, when said lever and the valve-lever R are in their normal position of

rest, (Fig. 1,) has its rounded side b² presented toward the rounded side m of the nose of the valve-lever and said rounded side of the nose of the operating-lever when the operating-lever is 70 pulled through its crank in the direction of the arrow D², swinging it by its elongated bearing upon the fulcrum-pin r, and against its weighted arm V, rides up and upon the said rounded side m of the nose of the valve-lever R, and finally from continuing to so swing 75 the lever its said nose passes over and beyond the upper end of the nose of the valve-lever, thereby bringing its straight and upright side or edge a² on the same side with the straight 80 and upright side or edge n of the nose of the valve-lever, to which it is presented by the then fall of the operating-lever, which, during the swing of the upper lever, above described, has lifted, the elongated fulcrum-bearing q of 85 the operating-lever allowing of the lift and fall thereof as the same is so swung upon its fulcrum-pin r, Figs. 1, 2, and 3. The crank portion X of the operating-lever is to be suitably connected by a chain or otherwise to any 90 suitable operating device—as, for instance, to the floor or door or seat of a water-closet, or to a handle, knob, or other pull—and when the operating-lever is operated through its crank portion, as above described, it first, 95 through its bearing d² of its arm W upon the surface f² of the arm Z of the valve-lever R, depresses said arm Z and raises the other arm, Q, of said valve-lever, lifting the valve from 100 its seat and opening the water-passage B, and continues to so depress the arm Z and to raise the arm Q of valve-lever until, from the continued swing of the two levers, the contact of the bearing d² of operating-lever U with surface f² of valve-lever R is broken by the 105 escape of each from the other at the end g² of the bearing surface f² of the valve-lever. While the operating-lever is depressing the arm Z and raising the arm Q of valve-lever R, as above described, and just about the 110 time the bearing-surfaces d² and f² of the two levers break contact at g², the bearing-surface b² of nose C² of operating-lever begins to press against the bearing-surface m of nose T of valve-lever, and thus to force the valve-lever 115 back to its normal position, and rest upon the abutment-block T² therefor, and, finally, riding upward over said surface m of nose T, the nose C² of operating-lever passes beyond and to the opposite side of nose T of valve-lever 120 and drops into a position at that side in which its edge or bearing-surface a² is presented to the edge or bearing-surface n of said nose T.

The bearing-surfaces a² and n of the noses of the two levers R and U remain in the position 125 stated so long as the power or force applied to the operating-lever to swing it to open the valve, as has been described, is continued. The return of the valve-lever to its rest, as above described, sets the valve free to return 130 to its seat as and in the manner hereinafter described, for the reason that the support of

the valve, through its stem O upon the loop P, is then removed.

On a release of the operating-lever, when its nose C² and the nose T of the valve-lever have their bearing-surfaces a² and n presented to each other, as above described, the weighted arm V of the operating-lever then works to return said lever to its normal position, and in so returning the edge a² of its nose 10 C² works against the bearing-surface or edge n of the nose T of valve-lever, and thereby raises the arm Q of said lever, lifting the valve from its seat, if it is then seated, and opening the water-passage B, if it is then closed, and 15 at the same time the nose C² of the operating-lever, riding over the nose T of the valve-lever, finally passes to the side thereof at which it was and from which it passed during the raising of the arm Q of the valve-lever 20 and the opening of the valve and water-passage from the working of the bearing d² of operating-lever upon the bearing f² of valve-lever, before described, and the lever U itself into its normal position and rest against the 25 abutment B² therefor.

After the nose of the operating-lever has passed the nose of the valve-lever, as described, the valve-lever and also the valve are released to their own motions, the lever to 30 turn to its rest upon its rest-block I² and the valve to return to its seat, as and in the manner hereinafter described. With the two levers again in their normal positions, they are in readiness for another operation thereof and 35 of the valve, as described.

From the above description it is apparent that a continuous pull upon the crank of the operating-lever U in the direction of the arrow D² secures, first, a lifting of the valve 40 from its seat, and then a location of the operating-lever U in relation to the valve-lever, to cause, on the return movement of the operating-lever, and when it is released to the action of its weighted arm, another lifting of 45 the valve. Again, it is apparent that in the operations of the levers R and U, above described, the valve-lever, at its end connected to the valve, in both operations to open the valve, moves in the same direction—that is, 50 upward—while the operating-lever, at its end connected for operating it, moves in opposite directions—that is, downward and upward. Consequently, for each of these operations to open the valve with a movement of the valve-lever in both of them in the same direction—that is, upward—at its end connected to the valve, and a movement of the operating-lever at its end connected for operating it in opposite directions—that is, downward and up- 55 ward—two different sets of working-bearings for the levers upon each other must be provided, those of one set at an angle more or less right to those of the other set, and one set for action during the downward movement, and the other set for action during the upward movement of the operating-lever at

its end connected for operating it, and the levers must be adapted to pass in their operation from action at and by one set of said sets of working bearings to action at and by the 70 other set thereof, all of which, under a construction and arrangement of the levers, substantially such as herein described, is obtained in a most practical and efficient manner; and as to the levers for opening the valve, as has 75 been described, this invention in substance consists in the combination of two levers, to wit: an operating-lever and a valve-lever, constructed and arranged to work in a relation to and upon each other substantially as herein 80 described—that is, so as to secure from an operating-lever from its movement in opposite directions, and from each of them, the movement of a lever connected to the valve in one and the same direction.

In Fig. 2 the valve is shown as lifted from the first operation and in Fig. 3 as lifted from the second operation of the levers to lift the same, and after either lift of the valve, as described, the valve is left to itself to close upon 90 its seat, because of the then immediate drop of the yoke-connection from its support under the shouldered end of the valve-stem by the return of the valve-lever to its normal position of rest upon the rest-block.

When the valve is lifted from its seat-opening, the discharge-pipe B of the tank in either of the operations of the levers R U described, as it is hollow, it at first floats upward through the water, and as the water-passage b at its 100 lower side is then opened to the water in the tank it begins to fill with water from the tank, the air of the valve passing out of it downward through the air-passage d, and thus it is finally sufficiently weighted to cause it to 105 fall to its seat, closing said discharge-pipe and entering its said water-passage b into the pipe K therefor, through which the water that has entered into the valve, when raised, as described, is then discharged, rendering the 110 valve capable of another operation, as before.

The first lifting of the valve described is for the purpose of securing what is known as a "preliminary wash," and the second lifting of the valve described is for the 115 purpose of securing what is known as the "after wash" of the water - closet bowl when the valve is used in connection with such bowls, and as the preliminary wash is only required to be small in quantity as compared with the quantity required for the after wash, the lever mechanism for lifting the valve is arranged so as to lift the valve from its seat but slightly for the preliminary wash, and, as a consequence, the closing of the valve 120 will be then secured more by the suction of the water rushing out of the tank through the discharge-pipe than by the filling of the valve with water, as described.

When the valve is off of its seat or open, the 130 pipe K, to make connection with the water-passage b of the valve when the valve is closed,

is open to the water in the tank, and to obviate any considerable waste of water in consequence thereof through said pipe it is preferable to use a pipe of small diameter and to contract its water-passage, as shown at k^2 , Fig. 1, such a pipe affording all necessary outlet for the escape of the water from the valve when the valve is closed.

The pipe L, making the air-passage d of the valve, together with the fixed collar M, guide the valve in its up-and-down movement, and it is preferable to suspend the valve from the yoke P so that the valve seated does not rest by its shouldered collar h upon the yoke, but is allowed a little vertical play thereat to insure a perfect closing of the valve upon its seat.

A valve having an air-passage, d, leading from its upper part downward, substantially as described, may have its water-passage b open directly into the discharge-pipe B instead of into a separate discharge, K, as described; and, again, the separate water-discharge-pipe H for the valve may be combined with an air-passage leading upward, or otherwise, from the valve instead of downward, as described; but in all cases air-communication must be had outside of the water contained in the tank, and a water-communication for the valve with the tank and with a suitable discharge to enable the water of the tank to enter said valve and to be discharged therefrom, substantially as described.

The yoke-connection herein shown and described between the valve and its lever may be dispensed with, and either a slack-chain connection, or, again, a wire rod or other rigid connection preferably hung at both ends to the valve and its lever may be substituted therefor.

If the connection of valve and valve-lever is a rigid one, as for instance, made by a wire rod, as aforesaid, dispensing with the yoke, the closing of the valve after being first opened by the downward swing of the operating-lever would be then insured by the forced return of the valve-lever to its seat on the rest-block T² by the working of the bearing faces or surfaces b² and m of the two levers, as hereinbefore described.

In lieu of arranging the operating-lever to lift and fall for its nose to ride and pass over the nose of the valve-lever, as shown and described, this arrangement of the operating-lever may be dispensed with, and the same result secured by a similar arrangement of the valve-lever, combined with a suitable spring or springs by which to force it back into position after the nose of the operating-lever has passed over and by its nose; again, both levers may be arranged to have a joint movement, such as has been described for each of them; again, this movement of either lever may be dispensed with and the noses themselves, either one or both, adapted to move for the one to pass by the other, and afterward to

return to their normal position—as, for instance in this manner, by hinging them or either of them to their respective lever and abutting them against the same, and combining with them springs suitably applied there-to and to the levers, to return them (the noses) to position after having swung to permit of the one nose to pass by the other, as desired, and by their abutment against the levers hold them firm for action, as the operating-lever is on its return or backward movement. These springs are to be also sufficiently stiff for the working of the nose-faces b² and m upon the valve-lever and valve herein described.

The hinging of the noses of the operating and valve levers above described is the subject in part of another application for Letters Patent of the United States on improvements in water-closet valves, filed by me November 26, 1884, Serial No. 148,912.

Concerning the mechanism herein described through which the valve is opened and allowed to close, it is apparent that the operating-lever has a reciprocating movement, that in the movement of the operating-lever in one direction it works by a face, d², thereof against a face, f², of an abutment which is connected to the valve, and thus the operating-lever raises or opens the valve, and after so opening the valve in the continuation of the movement of the operating-lever in the same direction the said working-face d² of said lever escapes from the said working-face f² of said abutment of the valve, and thus leaves it (the valve) free to close; and, furthermore, it is apparent that in the movement of the operating-lever in the other direction said lever works by a face, a², thereof against a face, n, of said abutment, and thus the operating-lever again raises or opens the valve, and after so opening the valve in the continuation of the movement of the operating-lever in the same direction the said working-face a² of said lever escapes from the said working-face n of said abutment of the valve, and thus leaves it (the valve) again free to close, and brings the working-face d² of said lever, which worked against said working-face f² of said abutment of the valve in the previous movement of the lever, and thus lifted the valve as aforesaid to position for operation to again lift or open the valve when the operating-lever is again moved in the proper direction therefor.

The mechanism for lifting the valves as herein described obviously may be used with valves of other constructions, and therefore it is not intended to limit said mechanism of itself to the particular valve shown. The adjustable set-screw t of the operating-lever enables the bearing of said lever upon the valve lever to be adjusted as desired.

Having thus described my invention, what I claim, and desire to secure by Letters Patent, is—

1. The combination, with the discharge-pipe B, of a tank, of a chambered valve, D, hav-

ing an air-passage, d , leading from its chamber downward into said discharge-pipe, and a suitable water-passage, b , substantially as described, for the purpose specified.

5 2. The combination, with the discharge-pipe B of a tank, of a chambered valve, D , having a suitable air-passage leading therefrom, and a water-passage, b , making connection with a discharge-pipe, K , substantially as described, 10 for the purpose specified.

15 3. The combination, with the discharge-pipe B of a tank, of a chambered valve, D , having an air-passage, d , leading from its chamber downward into said discharge-pipe B , and a water-passage, b , making connection with a discharge-pipe, K , substantially as described, 20 for the purpose specified.

25 4. The combination, with a tank for liquid, an outlet or discharge pipe for the liquid, and a valve to said outlet-pipe, of a reciprocating lever for operating said valve and having faces $d^2 a^2$, and of an abutment for said lever connected to the valve, and having faces $f^2 n$, and said lever and said abutment adapted in one movement of said lever for said lever to work by its face d^2 against the face f^2 of said abutment, and thus to lift and open the valve and then to escape therefrom and leave the valve free to close, and in the other movement of said lever for said lever to work by its face a^2 against the face n of said abutment, and thus to again lift and open the valve, and then to escape therefrom and leave the valve free to close, substantially as described.

35 5. The combination, with a tank for liquid, and an outlet or discharge pipe for the liquid, and a valve to said outlet-pipe, of a reciprocating lever for operating said valve, and having faces $d^2 b^2 a^2$, and of an abutment for said lever connected to the valve, and having faces $f^2 m n$, and said lever and said abutment adapted in one movement of said lever for said lever to work by its face d^2 against the face f^2 of said abutment, and thus to lift and open the valve, and then to escape therefrom, and also the face b^2 of said lever, from the face m of said abutment, and leave the valve free to close, and in the other movement of said lever for said lever to work by its face a^2 against the face n of said abutment, and thus to again lift and open the valve, and then to escape therefrom, leaving the valve free to close and to bring the faces $d^2 b^2$ of the lever and the faces $f^2 m$ of the abutment into position for 50 operation substantially as described.

6. The combination, with a valve to a water-passage, B , of an operating-lever, U , and a valve-lever, R , which is connected to said valve, and both levers constructed and arranged substantially as described, whereby, 60 from the movement of the operating-lever in opposite directions, the valve-lever is moved in the same direction, for the purpose specified.

7. The combination, with a tank for liquid, 65 an outlet and discharge pipe for the liquid, and a valve to said outlet-pipe, of a reciprocating lever for operating said valve, and having faces $d^2 a^2$, and of an abutment for said lever, which is carried by a reciprocating lever connected to the valve, and has faces $f^2 n$, and said lever and said abutment adapted in one movement of said lever for said lever to work by its face d^2 against the face f^2 of said abutment, and thus to lift and open the valve, 70 and then to escape therefrom and leave the valve free to close, and in the other movement of said lever for said lever to work by its face a^2 against the face n of said abutment, and thus to again lift and open the valve, and then to escape therefrom and leave the valve free to close, substantially as described.

8. In combination with a valve of a water-passage, B , a valve-lever, R , connected to said valve, and provided with bearing-surfaces f^2 , 85 m , and n , and an operating-lever, U , to operate lever R , and provided with bearing-surfaces d^2 , b^2 , and a^2 , which are arranged in relation to each other and to the said bearing-surfaces of valve-lever, and said levers arranged in relation to each other, and the whole operating from the forward and backward movement of operating-lever U , substantially as and for the purposes specified.

9. In combination with a valve for opening 95 and closing a passage, B , the operating-lever U , having bearing-surfaces $d^2 b^2 a^2$, weighted arm V , elongated bearing q , fulcrum-pin r , and abutment B^2 , and the valve-lever R , having bearing-surfaces $f^2 m n$, fulcrum k , and 100 abutment T^2 , substantially as and for the purposes and operations described.

In testimony whereof I have hereunto set my hand in the presence of two subscribing witnesses.

WILLIAM SCOTT.
